UNITED STATES PATENT OFFICE.

ROBERT M. DOWNIE, OF BEAVER FALLS, PENNSYLVANIA, ASSIGNOR TO KEYSTONE DRILLER COMPANY, OF BEAVER FALLS, PENNSYLVANIA, A CORPORATION OF PENNSYLVANIA.

EXCAVATOR-BUCKET MOUNTING.

1,228,654.

Specification of Letters Patent.

Patented June 5, 1917.

Application filed February 25, 1916. Serial No. 80,480.

To all whom it may concern:

Be it known that I, ROBERT M. DOWNIE, a citizen of the United States, residing at Beaver Falls, in the county of Beaver and 5 State of Pennsylvania, have invented a new and useful Excavator-Bucket Mounting, of which the following is a specification.

This invention has reference to mountings 10 and its object is to provide a mounting whereby the bucket is supported from and movable along a boom so as to be properly supported by the boom without undue lost motion due to wear, especially such wear as 15 is caused by accumulations of the material being excavated upon tracks provided on the boom for the bucket supporting means.

In accordance with the present invention 20 the boom has longitudinally disposed tracks which may be formed by constructing the boom of I or channel beams, and it is customary to provide the tracks on opposite sides of the boom.

The specific construction of the bucket 25 does not form a part of the present invention, but is shown, described and claimed in another application for an excavator bucket filed by me on even date herewith.

The present invention has to do with the 30 support for the bucket, comprising slides adapted to the tracks in the boom, each slide including a spacer bar or similar structure carrying wedge blocks constituting adjustable wear parts for the slide and adapted to 35 move along track strips fast to the boom in such manner that when unduly worn they may be removed and replaced by new strips. The wedges are so mounted on the spacer bars that they may be adjusted from time 40 to time when worn to take up wear liable to occur with considerable rapidity, because the tracks become more or less contaminated with the material, usually dirt being excavated. Materials like clay or sand are particularly liable to rapidly wear the contacting 45 parts of the slides and tracks. Experience has shown that wooden wedges provide suitable adjustable wear blocks, and hence it is desirable that the wear blocks of the 50 slide be made of wood or some other fibrous material answering the purpose.

In addition to the anti-wear qualities of the mounting adapting it especially for sandy and other quick-cutting soils, the

mounting has numerous other advantages. 55 The longitudinally extended slides distribute the weight to so great an extent lengthwise of the boom that there is no liability of bending the flanges of the channels, of which the boom is usually constructed, when 60 the boom is subjected to unusually heavy shocks, jars or loads.

All wear on the slides and boom is evenly 65 distributed. The slides in their travel along the boom effectively shove off small pebbles and other impedimenta, which in the case of wheeled trolleys frequently used in excavating machines to carry the bucket or scoop, are crushed and ground by the wheels and serves to increase the wear upon the 70 boom and trolleys.

The slides can be repaired on the road often with material obtainable along the road and at practically no cost, while the necessity of repairs is so infrequent that the 75 cost of repairs is practically negligible.

The slides permit the practically exact adjustment of the line of cut of the scoop or bucket, because the slides may be readily adjusted to eliminate any play, this being out 80 of the question where the scoop or bucket is carried by a wheeled trolley traveling along the boom. This feature is particularly important where it is necessary to skim off a few inches of roadbed for resurfacing, since 85 the depth of cut may be very accurately set and maintained.

In the event of the boom dropping sufficiently for the scoop or bucket to suddenly 90 strike the ground, the wood blocks interpose cushions between the bucket and boom, thus relieving the jar which would otherwise occur.

The slides permit the introduction of sufficient friction between the slides and boom to 95 hold the scoop or bucket in position and against sliding along the boom under the action of gravity while the scoop or bucket is being dumped.

The invention will be best understood 100 from a consideration of the following detailed description, taken in connection with the accompanying drawings forming part of this specification, with the further understanding that while the drawings show a 105 practical form of the invention, the latter is not confined to any strict conformity with the showing of the drawings, but may be

changed and modified so long as such changes and modifications come within the scope of the appended claims.

In the drawings:—

5 Fig. 1 is a side elevation of the bucket slide or support of the present invention.

Fig. 2 is a plan view thereof showing a portion of the boom in part broken away.

10 Fig. 3 is a front elevation of the bucket with one slide in elevation and the other in section at the corresponding bucket hanger, and also showing the boom in cross-section.

15 Fig. 4 is a rear elevation of the bucket with some parts connected thereto shown in cross-section.

Fig. 5 is a section on the line 5—5 of Fig. 2 showing one slide and the corresponding portion of the boom, the bucket being omitted.

20 Referring to the drawings, there is shown a boom 1, which in the particular form illustrated comprises spaced I beams 2 connected at suitable intervals by plates 3, whereby the two I beams are joined together to constitute 25 the boom with the outside channels of the I beams exposed on opposite sides of the boom. It will be understood, of course, that the same effect so far as channels are concerned would result if the boom were made up of 30 channel beams, or were constructed in any suitable way to provide tracks or channels, for a purpose to be described.

There is also shown a bucket 4, which, because of the manner of operation, may be 35 designated a scoop or shovel, being open at what constitutes the top and bottom in the operative position of the bucket, and also at the front, and having a dumping bottom 5 joined to the front portion of the scoop or 40 shovel by pivots 6. The front of the bottom 5 extends beyond the front of the scoop and there carries cutting teeth 7 designed to enter the material to be excavated to loosen it, so that it may be directed into the interior of 45 the scoop when the latter is moved over or skims the surface of such material. The bottom 5 is of such size as to permit it to be moved into the scoop 4 through the bottom thereof to desired distances. The rear end 50 of the bottom 5 carries a latch plate 8 and a guard block 9, while shoes or runners 10 on the under face of the bottom 5 serve to protect it from undue wear when moved over or into the material to be excavated. 55 The scoop is provided with a rear wall 11, which may or may not be in one piece with the sides of the scoop. Extending about the rear end of the bucket at the upper edge of the back wall is a reinforcing strip serving 60 to stiffen and otherwise strengthen the scoop.

Secured to the outer or rear face of the back 11 is a latch lever 12 carried by a bracket 13 fast to the rear wall of the scoop, 65 and the latch lever is furnished with a series

of perforations 14 for the reception of a pivot bolt traversing the bracket 13, whereby the latch lever may be adjusted up and down on the back of the scoop to hold the dumping bottom 5 in different positions of inclination with respect to the body of the scoop, thus varying the inclination of the teeth 7 without correspondingly varying the body of the scoop. The latch lever 12 is urged to the engaging position by a spring 15 and is 75 controlled by an actuating lever 16 adapted to be moved from a distance, as by a jerk rope or otherwise.

In order to move the scoop it is provided with a U-bolt 17 secured to the rear wall 11 80 of the bucket, or with any other suitable means whereby a wire rope or cable, or other line, may be made fast to the bucket.

So far as the construction of the boom and bucket is concerned, it may follow the same 85 lines as set forth in the aforesaid application, and no claim is made herein to the construction of the bucket *per se*, since claims to such construction are made in the aforesaid companion application.

90 Secured to the inner faces of the outer marginal webs of the boom are track strips 18 held thereto by rivets 19 or otherwise, so that these strips may be renewed from time to time by knocking off the heads of the 95 rivets, removing the worn strips, and replacing them with unworn strips which may be riveted to the boom the same as the original strips were fastened thereto. The strips 18 may be made of steel and require renewal 100 but occasionally, since the wear of such strips affects them but slowly.

105 Adapted to each side channel of the boom is a slide composed of an elongated spacer bar 20 carrying adjustable wedges 21. The spacer bar is shown as tapering in width from the ends toward the central portion, although such particular direction of taper is not obligatory. Each wedge 21 is in the form of a taper block corresponding to the 110 taper of the spacer bar, so that the spacer bar is supported intermediately of the track strips 18 with one edge of each wedge block engaging the corresponding taper portion of the spacer bar, and the other edge of the 115 wedge block engaging the corresponding track strip 18 with the edges engaging the track strips substantially parallel one with the other. In this way the slide, which, as will presently appear, constitutes the bucket 120 support, is capable of being moved lengthwise of the boom in relatively snug fit to the tracks 18, but without binding thereto. At the thick end of each wedge block 21 there is a plate 22 let into the block and secured thereto by screws 23 or in any other appropriate manner. The plate has one end 24 projecting beyond the thick end of the wedge block and there traversed by a set screw 25 entering one of a series of tapped 125 130

sockets 26 in the spacer bar, the sockets being arranged in series lengthwise of the bar near the intermediate or narrow portion thereof.

5 Each spacer bar near its ends carries a transverse guide strip 27 overlapping the corresponding narrow ends of the wedge blocks 21, so as to prevent any pivotal action of the wedge blocks on the single screws 10 25 each holding a plate 22 to the spacer bar.

Secured to each spacer bar near what constitutes the front end thereof is one leg of a hanger 28 secured to and rising from the inner face of the rear wall 11 of the bucket, 15 with the legs of the hanger so spaced as to be exterior to the outer faces of the two slides when properly lodged in the channels of the boom. Each leg of the hanger bracket 28 contains a longitudinally extended series 20 of holes or perforations 29 for the reception of a stud bolt 30 held in place by a nut 31 and having a stud extension 32 entering the front end portion of the spacer bar 20. The stud bolts 30 and perforations 29 permit the 25 adjustment of the hanger bracket 28 to raise or lower the bucket with reference to the beam.

The bracket 28 serves to maintain the front end of the slides in the track channels 30 of the boom. The rear ends of the slides are similarly maintained by a yoke 32 secured to the spacer bar near its rear end by bolts 33 which may also be stud bolts. These bolts each traverse one web of a corresponding 35 angle brace bar 34 extending and connected to the bucket near the bottom thereof by a bolt 35 or otherwise. These brace bars serve to hold the bucket against pivotal action about the stud bolts 30 with the 40 slides or bucket supports in the main located to the rear of the scoop or bucket. The brace bars 34 are reinforced by cross brace strips 36 made fast at spaced points to the brace bars, and they are further reinforced by a 45 bolt 37 extending through the brace bars near their rear ends. The yoke 32^a is held against swinging movements about the stud bolts 33 by a link 38 connecting the yoke 32^a at a point about midway of its length to the 50 bolt 37 at a point about midway of the length of the latter.

With a slide and supporting means therefrom to the bucket or scoop, the latter is carried by the rear end only and may be tilted 55 with respect to its line of travel along the boom. At the same time wear in the slide, which is liable to occur between the wedge blocks and the track strips, is readily taken up as becomes necessary by adjusting the 60 wedges toward the corresponding ends of the spacer bar, this being accomplished by removing the screws 25 and replacing them in the next sockets 26 in order. The sockets are staggered on opposite sides of the spacer 65 bar on the same side of the mid point there-

of, so as not to interfere one with the other, and so as to provide many adjustments. With this arrangement the wedge blocks on, say, the top of the spacer bar may be adjusted to take up wear, and when adjustment is again needed the wedge blocks on the bottom of the spacer bar may be so adjusted, and so on until no more adjustments are provided for. By this time the wedge blocks have become worn so thin that new 70 wedge blocks are needed, and these may be provided at small cost, restoring the slide or carrier to substantially its original condition. The track strips 18 will out wear many sets of wedge blocks, which latter are 75 made of wood or other material of an anti-friction nature with respect to the steel track strips, so that renewal of the track strips is of infrequent occurrence. Moreover, the track strips protect the webs of the 80 boom from all wear, and hence no renewals 85 so far as the boom itself are concerned, are needed.

The slides permit the maintenance of the fit between them and the boom in such condition that undue lost motion need not occur, nor need there be undue friction between the slides and the boom. Because of such arrangement the scoop is readily moved along the boom by power when the 90 boom is in a substantially horizontal position, so that the scoop will engage a roadway or other surface to remove accumulations of dirt or to grade the surface, and when the scoop is filled it is only necessary 95 to tilt the boom in a manner to elevate the front end of the bucket, and then swing the boom to one side or the other to a point of disposal of the dirt contained within the 100 scoop, the latter being readily dumped by 105 means of the dumping bottom. The elevation of the boom correspondingly elevates the scoop, which in the operation of the dredging machine has in its active movement been drawn to near the front end of 110 the boom, the other end of the boom being suitably mounted on the body of the dredging machine. This means that when the boom is elevated the scoop is relatively high 115 in the air, and to return it to a low position 115 close to the dredging machine it is only necessary to slacken the line by which the scoop is moved forwardly, whereupon the scoop will gravitate to the lower position, because the slides need not engage the tracks with 120 such frictional force as to prevent such gravitating movement.

What is claimed is:—

1. In an excavating machine, the combination with an elongated boom having 125 longitudinal runways and a scoop or shovel supported by the boom and movable lengthwise thereof, of a supporting slide structure for the scoop or shovel adapted to the runways of the boom, said slide structure in- 130

cluding spacer bars and shoes on the spacer bars engaging in the runways and slidable therealong, a supporting connection between one end of the spacer-bar portion of the 5 slide structure and the rear end of the scoop or shovel, and brace bars between the other end of the spacer bar portion of the slide structure and the rear end of the scoop or shovel.

10 2. In an excavating machine, the combination with an elongated boom having longitudinal runways and a scoop or shovel supported by the boom and movable lengthwise thereof, of a supporting slide structure 15 for the scoop or shovel adapted to the runways of the boom, said slide structure including spacer bars and shoes on the spacer bars engaging in the runways and slidable therealong, a supporting connection between 20 one end of the spacer-bar portion of the slide structure and the rear end of the scoop or shovel, and brace bars between the other end of the spacer bar portion of the slide structure and the rear end of the scoop or 25 shovel, the supporting connection being in the form of a hanger secured to the upper portion of the rear end of the bucket and the brace bars being connected to the bucket near the lower portion of the rear end of 30 the bucket.

3. In an excavating machine, the combination with an elongated boom having longitudinal runways and a scoop or shovel supported by the boom and movable length- 35 wise thereof, of a supporting slide structure for the scoop or shovel adapted to the runways of the boom, said slide structure including spacer bars and shoes on the spacer bars engaging in the runways and slidable 40 therealong, a supporting connection between one end of the spacer-bar portion of the slide structure and the rear end of the scoop or shovel, and brace bars between the other end of the spacer bar portion of the slide 45 structure and the rear end of the scoop or shovel, the supporting connection being secured to the upper end of the rear of the bucket and having adjustable connections to the corresponding end of the spacer bar 50 portions of the slide, and the brace bars having pivotal connections at opposite ends to the spacer bar parts of the slide and the lower portion of the rear end of the bucket, respectively.

55 4. In an excavating machine, the combination with an elongated boom having channel runways on opposite sides and a scoop or shovel supported by the boom and movable lengthwise thereof, of a slide structure 60 for supporting the bucket comprising slides adapted to the runways on the boom, each slide consisting of an elongated spacer bar increasing in width from the mid portion toward the ends, and wedge blocks or shoes 65 on and adjustable lengthwise of the spacer

bar to maintain a snug fit of the slide in the respective runway by compensating for wear.

5. In an excavating machine, an elongated boom having channel runways on opposite sides, an excavating scoop or shovel, slides adapted to the respective runways and each comprising an elongated spacer bar tapering from the ends toward the middle portion, wedge blocks secured to and adjustable 70 along the taper portions of the spacer bar, hangers connected to the front ends of the slides and to the rear end of the scoop, and brace bars connected to the rear ends of the slides and the rear end of the scoop adjacent to the bottom thereof. 75

6. In an excavating machine, an elongated boom having channel runways on opposite sides, an excavating scoop or shovel adapted to move lengthwise of the boom, elongated 80 slides each adapted to a respective runway of the boom and comprising an elongated spacer bar tapering from the ends toward the middle portion, and elongated wedge blocks adjustable lengthwise of the taper 85 portions of the spacer bar, a suspension member connected to the front ends of the spacer bars and maintaining the slides in the channel runways of the boom, and brace bars each connected at one end to the respective spacer bar near the rear end of the latter and at the other end connected to the rear end of the scoop or bucket adjacent to the bottom of the latter. 90

7. In an excavating machine, an elongated boom having channel runways on opposite sides, an excavating scoop or shovel adapted to move lengthwise of the boom, elongated slides each adapted to a respective runway of the boom and comprising an 100 elongated spacer bar tapering from the ends toward the middle portion and elongated wedge blocks adjustable lengthwise of the taper portions of the spacer bar, a suspension member connected to the front ends of the 105 spacer bars and maintaining the slides in the channel runways of the boom, and brace bars each connected at one end to the respective spacer bar near the rear end of the latter and at the other end connected to the rear end of the scoop or bucket adjacent to the bottom of the latter, the rear 110 ends of the spacer bars being also connected by a yoke for maintaining said rear ends of the spacer bars in the runway channels 115 of the boom. 120

8. In an excavating machine, the combination with an elongated boom having opposite runway channels therein, and an excavating scoop or shovel adapted to be carried by and moved lengthwise of the boom, of a supporting structure for the scoop or shovel having elongated slides adapted to the respective runways on opposite sides of the boom, each slide comprising an elongated 125 130

- gated spacer bar tapering from the ends toward the central portion, wedge blocks adapted to the taper portions of the spacer bar with each wedge block and the spacer bar having coating means for the adjustment of the wedge lengthwise of the spacer bar, and supporting connections between the spacer bar and the scoop.
9. In an excavating machine, a boom having runways, and an excavating scoop or shovel mounted on the boom and provided with slides entering the runways and supporting the scoop, said slides having adjustable members for maintaining a snug fit in the slides and runways.
10. In an excavating machine, a boom having longitudinal runways with removable tracks therein, and an excavating scoop or shovel movable lengthwise of the boom and provided with supporting slides adapted to the runways and tracks, each slide comprising a spacing bar to which the scoop is connected, and shoes removably secured to the spacing bar on the top and bottom thereof and provided with adjusting means, whereby wear of the shoes may be taken up to maintain a suitably snug fit of the shoes on the track.
11. In an excavating machine, a boom having channels on opposite sides constituting runways, and an excavating scoop or shovel carried by and movable lengthwise of the boom, the carrying means for the scoop including slides movable along the runways in the boom and having means for expanding the runway-engaging portions of the slides laterally of the boom to compensate for wear.
12. In an excavating machine, a boom having channels on opposite sides constituting runways, and an excavating scoop or shovel carried by and movable lengthwise of the boom, the carrying means for the scoop including slides movable along the runways in the boom and having means for expanding the runway-engaging portions of the slides laterally of the boom to compensate for wear, said runway-engaging portions of the slides comprising readily renewable shoes of fibrous material of anti-friction characteristics with respect to the material of the runways.
13. In an excavating machine, a boom having longitudinal channels constituting runways, and an excavating scoop or shovel hung from the boom and movable lengthwise thereof and provided with elongated slides adapted to the channels in the boom, said slides each comprising a spacer bar carrying the scoop, and wedge-shaped shoes of wood removably attached to the spacer bar and adjustable lengthwise of the latter to take up wear.
14. In an excavating machine provided with a scoop-supporting boom having elongated runways, an elongated scoop-carrying slide structure adapted to the runways and having shoes thereon slidable in the runways and adjustable to vary the width of the part of the slide structure engaging the runways to compensate for wear.
15. In an excavating machine provided with a scoop-supporting boom having elongated runways, an elongated scoop-carrying slide structure adapted to and movable along the runways and having elongated shoes thereon slidable in the runways and adjustable at an angle to both the length and width of the slide structure to vary the width of that part of the slide structure engaging the runways to compensate for wear.
16. In an excavating machine provided with a scoop-supporting boom having elongated runways, an elongated scoop-carrying slide structure having intermediate parts to which the scoop is secured, and elongated shoes on the intermediate parts engaging the runways, the shoe portion of the slide structure having means provided for adjustment to vary the width of the slide structure in the runways to compensate for wear.
17. In an excavating machine, the combination with a boom having longitudinal runways, of a slide structure mounted in and movable lengthwise of the runways, and a scoop suspended from the slide structure at points spaced apart lengthwise of said slide structure.
18. In an excavating machine, the combination with a boom having longitudinal runways on opposite sides, of slides in the respective runways; and a scoop suspended from the slides at points on each slide spaced apart in the direction of the length of the slide.
19. In an excavating machine, the combination with a boom having longitudinal channels on opposite sides, elongated slides mounted in the channels, and a scoop suspended from opposite end portions of each slide.
20. In an excavating machine, the combination with a boom having longitudinal channels on opposite sides, elongated slides mounted in the channels, and a scoop suspended from opposite end portions of each slide, each slide having adjustable wooden wear blocks engaging corresponding portions of the runways.
- In testimony, that I claim the foregoing as my own, I have hereto affixed my signature in the presence of two witnesses.
